STACKING MACHINE

Lyle F. Shabram, Danville, Calif., assignor to Consolidated Thermoplastics Company, Stamford, Conn., a corporation of Delaware

Filed Oct. 10, 1960, Ser. No. 61,700

4 Claims. (Cl. 198—35)

This invention relates to stacking machines and, in particular, to a machine for taking articles from a relatively high velocity belt or the like and depositing the articles at an outlet device at a relatively low velocity. The machine is especially adapted for use with high speed bag-manufacturing equipment such as that shown in my copending application entitled Apparatus for Forming Articles From a Web, Serial No. 70,481, filed November 21, 1960, and assigned to the same assignee as the present application. But, of course, it is not limited to this one use.

It is an object of the invention to provide a machine for picking up articles, such as plastic bags, from a continuous high velocity source and depositing the articles on a low velocity or stationary outlet device. Another object is to provide a stacking machine having a variable release point so that articles can be deposited in vertical stacks on a stationary outlet or in closely overlapped layers on a slow moving outlet using a fixed release point, and in vertical stacks on a moving outlet using an oscillating release point.

It is an object of the invention to provide a machine for removing articles from a continuous source and including a plurality of arms with each arm having an article-gripping section and a drive section, a track having an arcuate section and a relatively straight section, means for engaging the drive section of each of the arms and driving the arms around the track with the article-gripping section projecting from the track whereby the gripping section of an arm has a relatively high velocity when the arm is traversing the arcuate section and a relatively low velocity when traversing the straight section, and with the gripping section of an arm passing through a first position adjacent the source while traversing the arcuate section and passing through a second position adjacent the outlet while traversing the straight section, and control means for energizing the article-gripping section of each arm while the arm is passing from the first position to the second position to remove an article from the source at the first position and deposit the article on the outlet at the second position.

It is an object of the invention to provide a machine for removing articles from a high velocity belt and stacking the articles on a low velocity belt including a plurality of arms with each arm having an article-gripping section and a drive section and with the gripping section including a vacuum line with a plurality of outwardly directed inlets, a track having an arcuate section and a relatively straight section, means for engaging the drive section of each of the arms and driving the arms around the track with the article-gripping section projecting from the track whereby the gripping section of an arm has a relatively high velocity when the arm is traversing the arcuate section of the track and a relatively low velocity when traversing the straight section, and with the gripping section of an arm passing through an article-pickup position adjacent the high velocity belt while traversing the arcuate section and passing through an article-release position adjacent the low velocity belt while traversing the straight section, and control means for connecting a vacuum source to the vacuum line of each arm while the arm is passing from the article pickup to the release position. Another object is to provide a stacking machine wherein the article-gripping section of

2

each arm passes below and adjacent the high velocity belt while the arm is moving along the arcuate section of the track to pick up an article from the belt and wherein the article-gripping section is positioned above the low velocity belt when the arm is moving along the straight section of the track and the vacuum is shut off to permit the article to be deposited onto the low velocity belt. A further object is to provide a stacking machine including a source of air under pressure in the central area of the machine to provide an outwardly directed air current over the arms as an aid in controlling the relatively large and flimsy articles as they are moved from one belt to the other.

The invention also comprises novel details of construction and novel combinations and arrangements of parts, which will more fully appear in the course of the following description. The drawings merely show and the description merely describes a preferred embodiment of the present invention which is given by way of illustration or example.

In the drawings:

FIG. 1 is a side elevation of a plastic bag-manufacturing apparatus having the stacking machine of the invention at the output end thereof;

FIG. 2 is an end view taken along the line 2—2 of FIG. 1;

FIGS. 3 and 4 comprise an enlarged sectional view taken along the line 3—3 of FIG. 1;

FIG. 5 is a sectional view taken along the line 5—5 of FIG. 3;

FIG. 6 is a sectional view taken along the line 6—6 of FIG. 3;

FIG. 7 is a sectional view taken along the line 7—7 of FIG. 3;

FIG. 8 is a sectional view taken along the line 8—8 of FIG. 3;

FIG. 9 is a sectional view taken along the line 9—9 of FIG. 3;

FIG. 10 is a sectional view taken along the line 10—10 of FIG. 4; and

FIG. 11 is a partial view taken along the line 11—11 of FIG. 4.

FIGS. 1 and 2 depict a bag-making machine 14 having a stacking machine 15 positioned at the output end thereof. The bag-making machine 14 includes a drive motor 16, a heat-sealing drum 17, an endless belt 18, and a roll stand 19, and is described in detail in my aforementioned copending application. The motor 16 drives the drum 17 through a belt 20 and gear 21. The drum, in turn, drives the endless belt 18 which passes between rolls 22, 23, over rolls 24, 25, around the drum 17, over rolls 26, 27, 28, and over rolls 29, 30 of a belt-tensioning device. In the particular embodiment shown herein, the stacking machine 15 and a conveyor belt 31 are also driven from the motor 16, via the belt 20, a worm gear 32, a shaft 33, right angle drives 34, 35 and a chain 36. The belt 31 and a variable speed transmission 37 are driven from the chain 36, the transmission 37 driving the stacking machine 15 through another chain 38. This type of drive provides a direct speed relation between the drum 17, the conveyor belt 31 and the stacking machine 15, but of course any suitable drive may be used for each of the units.

In the operation of the machinery, a roll 40 of material such as polyethylene film is mounted in the roll stand 19 and a strip 41 of the material, which is ordinarily folded double, is fed from the roll 40 into engagement with the endless belt 18 between the rollers 22, 23. The drum 17 carries appropriate heat-sealing electrodes which form the strip of material into the desired articles. Typically, the product of the machine will be rectangular bags 42 having a folded edge at the bottom and heat-

sealed edges at each side. The heat-sealing electrodes of the drum 17 may separate the bags from each other or may only partially separate them so that a continuous web of material leaves the drum. The stacking machine of the present invention is suitable for use with either type of operation.

The stacking machine 15 includes a plurality of arms 50, each having means for gripping a bag at the extremity thereof. The arms are driven around a track having an arcuate section and a straight section so that the extremities of the arms move at a relative high velocity while an arm is traversing the arcuate section and at a relatively low velocity when an arm is traversing the straight section of the track. The stacking machine is positioned relative to the source of articles, here the belt 18 of the bag-making machine 14, so that an arm is traversing the arcuate section of the track when the extremity thereof is adjacent the source. The speed of the stacking machine is adjusted so that the velocity of the arm extremity is about the same as that of the belt 18 so that the arm can easily pick up the bag from the belt. The stacking machine is also positioned relative to the outlet, here the conveyor belt 13, so that the arms are traversing a straight section of the track when the arm extremity is over the outlet. Then the arm extremity is moving at a much slower velocity and the bag can be deposited on the belt in any of several styles to be described hereinbelow.

The stacking machine is shown in greater detail in FIGS. 3 and 4 and the remaining figures. The machine includes vertical frame members 51, 52 carrying bearing blocks 53, 54 respectively. A stepped tubular shaft 55 is mounted between the frame members in the bearing blocks and a solid shaft 56 is positioned within the tubular shaft 55 and rotates in bearings mounted in the bearing blocks 53, 54.

Each of the arms 50 is in the form of a U-shaped tube having a fitting 59 at one end and a fitting 60 at the other. Each of the fittings 59 is fixed between T-shaped links of a link chain belt 61 and each of the fittings 60 is similarly mounted in a belt 62. The construction and operation of the belt 61, 62 is essentially the same and the belt 62 will be described as typical. This structure is best seen in FIGS. 5, 8 and 9.

The chain 62 runs over sprockets 63, 64 carried on shafts 65, 66, respectively. The shaft 65 is mounted in bearings in the bearing block 53 and the shaft 66 is mounted in bearings in the bearing block 67 which is also mounted on the frame member 51. The block 67 is slidable horizontally relative to the block 53 for adjusting the belt tension, fine adjustment being provided by screws 68 carried in the block 53. The shaft 65 is driven from the variable speed transmission 37 via the belt 38 which runs over a sprocket 70. The corresponding shaft for the chain belt 61 on the other side of the machine is driven from the shaft 65 through gears 71, 72, the shaft 56, and a corresponding set of gears indicated at 73 (FIG. 4). The two sprockets 63, 64 provide a track along which the arms 50 travel, the arms following an arcuate path when the belt engages the sprocket and following a straight path between the sprockets.

If desired, means may be provided with the belt track to provide a smooth transition between the arcuate section and the straight section. One such means is shown in FIGS. 5 and 9 in the form of a shoe 74 mounted on the frame member 51 and within the loop of the belt 62. The shoe is provided with a cam surface 75 which engages the belt while moving through the arcuate section of the path and provides a gradual change of curvature to the following straight section. A similar shoe is provided for the belt 61 on the opposite side of the machine.

A plurality of slits 77 is provided along the outer edge of the bight of each of the U-shaped arms 50 to provide

means for gripping a bag and picking the bag from the belt 18. A vacuum source is connected to each of the tubular arms through the fitting 60, providing a suction at the slits 77. The vacuum on each individual arm is controlled so that the vacuum is turned on prior to arrival of an arm at the bag-pickup position, indicated at A of FIG. 5, and is shut off when the arm is at the bag-deposit or release position, indicated at B. Each of the fittings 60 may be connected to a corresponding port 78 in a port plate 79 through a flexible line 80. The port plate 79 is fixed to a sleeve 81 which in turn is mounted on the tubular shaft 55 with bearings 82. The sleeve 81 includes a spur gear 83 driven through an idler gear 84 from another gear 85 carried on the shaft 65 for rotation of the port plate in synchronism with the arms 50.

Control of vacuum to the individual ports 78 and, hence, to the individual arms 50 is carried out through a manifold plate 87 fixed on the shaft 55. The manifold plate 87 is positioned against the port plate 79 with a valve seat 88 of Teflon or other suitable material positioned therebetween. A plurality of circumferentially spaced pins 89 is carried in the port plate 79, riding in an annular groove 90 in the manifold plate to maintain alignment of the two plates. A flexible line 91 (FIGS. 2 and 7) provides communication between a manifold passage 92 in the manifold plate and the interior of the tubular shaft 55. Another line 93 which may be coupled to a remote vacuum source, is mounted in the bearing block 53 for communication with the interior of the tubular shaft 55 (FIGS. 3 and 8). O-rings 94, 95 provide seals between the shafts 55, 56 to provide a closed flow path from the manifold passage 92, through the line 91 and the shaft 55 to the line 93. The manifold passage 92 occupies about 180° of arc so that the vacuum source is connected to an arm at some time before the arm approaches position A and is disconnected when the arm is at position B. By having the passage 92 cover a greater portion of the revolution than is required for moving from position A to position B, the specific location of position B can be varied without affecting the location of position A.

Another manifold passage 96 may be provided in the manifold plate 87 to vent the arms to the atmosphere at an opening 97 for release of the bags. A source of air under pressure can be connected to the passage 96 in the same manner that the vacuum is connected to the passage 92 to provide an air blast at the slits 77 in the arms to accelerate release of the bags if desired. It has been found that such is not necessary in most applications of the machine. Also, the passage 96 may be used to direct heating or cooling air through the arms during this portion of the operating cycle.

A lever 98 is fixed in a ring 99 mounted on the tubular shaft 55 and provides for rotation of the shaft and the manifold plate 87 relative to the frame of the machine. The lever 98 may be manually operated or may be motor driven as desired. Rotation of the lever provides the above-discussed adjustment of the location of point B where the vacuum is shut off from the arms.

In the handling of lightweight flexible articles such as very thin film polyethylene bags, it has been found that the stacking operation is facilitated by providing a continuous outward flow of air past the arms 50. One arrangement for providing the outward air flow, which is similar to the arrangement for the vacuum source, is shown in FIG. 4. A plurality of openings 100 is provided in the tubular shaft 55 to the right of the O-ring seal 94. An inlet line 101 is fixed in the block 54 providing a flow path from an external air source to the interior of the tubular shaft 55 between the seal 94 and another O-ring seal 102. In an alternative arrangement, an electric motor-driven blower could be mounted directly on the shaft 55 with the blower inlet connected to the manifold plate 87 to serve as the vacuum source and with the

blower discharge providing the outwardly directed air flow past the arms of the machine.

The operation of the stacking machine is best seen in conjunction with FIGS. 1, 2 and 5. In a typical installation, the belt 18 of the bag-making machine will be moving at a rate of five hundred to eight hundred feet per minute while the outlet conveyor belt 31 may move at less than one tenth this speed, i.e., about thirty-five feet per minute. A continuous line of bags 42 will be carried along by the belt over the roller 26 and over the roller 27 and past the position A. The stacking machine is located so that the extremity of an arm touches or almost touches a bag adjacent its leading edge. At this point, the arm is moving over an arcuate section of the track so that the extremity is travelling at a relatively high velocity. Also, the vacuum source is connected to the arm so that the arm will pick up the bag from the belt. It is preferred to pick up the bags from the underside of the high speed belt so that they may be dropped onto the low speed belt and this is easily accomplished with the present machine as the bags are held to the belt by the static charge thereon until pulled away by the arm. As indicated previously, the bags may be severed from each other or may be only partly severed. With partly-severed bags, it is preferred to have the extremity of an arm moving at a slightly higher velocity than the belt at the pickup position so that a tension force is applied to the junction between the bags for severing the bags.

Each bag is carried from position A to position B at which time the vacuum in the arm is cut off and the bag drops onto the belt 31. The outward air currents, indicated by the arrows in FIG. 5, tend to push the trailing edges of the bags outward and prevent a following bag from being stacked underneath a preceding bag. When the belt 31 is run at a steady slow rate and the vacuum is cut off at the same point for every arm, the bags are stacked on top of each other with each bag overlying a major portion of the next lower bag, the overlap being a function of the size of the bag and the relative velocities of the high speed and low speed belts. In an alternative mode of operation, the belt 31 may be advanced stepwise with the belt remaining stationary for receiving a vertical stack of bags and then being rapidly advanced approximately one bag length to receive another vertical stack of bags.

In another alternative mode of operating the mechanism, the lever 98 may periodically be shifted and then returned to the initial position to provide a periodic decrease in the amount of overlap which serves as an indicator for a predetermined number of bags, permitting the group to be lifted from the belt as a unit. In another alternative mode of operation, the lever 98 may be advanced to move the point B forward at the same rate as the belt 31 so that successive bags are deposited in a vertical stack. After a stack of predetermined height has been created, the lever is rapidly returned to the initial position and then advanced at the belt rate to provide a new vertical stack adjacent the preceding vertical stack. Of course, other outlet devices can be substituted for the conveyor belt 31 to receive the bags from the slowly moving arms.

Although exemplary embodiments of the invention have been disclosed and discussed, it will be understood that other applications of the invention are possible and that the embodiments disclosed may be subjected to various changes, modifications and substitutions without necessarily departing from the spirit of the invention.

I claim as my invention:

1. In a machine for removing articles from a relatively high velocity belt and stacking the articles on a relatively low velocity belt, the combination of: a plurality of arms, each of said arms having an article-gripping section and drive section, said gripping section including a vacuum line with at least one outwardly directed inlet; a track having an arcuate section and a relatively straight section;

means for engaging the drive section of each of said arms and driving said arms around said track with the article-gripping section projecting radially from said track, whereby the gripping section of an arm has a relatively high velocity when the arm is traversing the arcuate section of the track and a relatively low velocity when the arm is traversing the straight section, and with the gripping section of an arm passing through an article pickup position adjacent the high velocity belt while traversing said arcuate section and passing through an article-release position adjacent the low velocity belt while traversing said straight section; and control means actuated as a function of position of an arm along said track for connecting a vacuum source to the vacuum line of each arm while the arm is passing from said article pickup position to said release position.

2. In a machine for removing articles from a relatively high velocity belt and stacking the articles on a relatively low velocity belt, the combination of: a plurality of arms, each of said arms having an article-gripping section and drive section, said gripping section including a vacuum line with at least one outwardly directed inlet; a track having an arcuate section and a relatively straight section; means for engaging the drive section of each of said arms and driving said arms around said track with the article-gripping section projecting radially from said track, whereby the gripping section of an arm has a velocity approximately that of the high velocity belt when the arm is traversing the arcuate section of the track and a velocity approximately that of the low velocity belt when the arm is traversing the straight section, and with the gripping section of an arm passing through an article-pickup position adjacent and below the high velocity belt while traversing said arcuate section and passing through an article-release position adjacent and above the low velocity belt while traversing said straight section; and control means actuated as a function of position of an arm along said track for connecting a vacuum source to the vacuum line of each arm while the arm is passing from said article pickup position to said release position.

3. In a machine for removing film-like articles from a relatively high velocity source and depositing the articles in overlying relation on an outlet, the combination of: a plurality of arms, each of said arms having an article-gripping section disposed substantially orthogonal to a drive section, said gripping section including a vacuum line with at least one outwardly directed inlet; a track having an arcuate section and a relatively straight section; an endless belt riding on said track and engaging the drive section of each of said arms for driving said arms around said track with the article-gripping sections projecting outwardly from said track and enclosing a zone as they travel around said track, whereby the gripping section of an arm has a relatively high velocity when the arm is traversing the arcuate section of the track and a relatively low velocity when the arm is traversing the straight section, and with the gripping section of an arm passing through an article-pickup position adjacent the source while traversing said arcuate section and passing through an article-release position adjacent the outlet while traversing said straight section; control means actuated as a function of position of an arm along said track for connecting a vacuum source to the vacuum line of each arm while the arm is passing from said article pickup position to said release position; and a source of air under pressure positioned within said zone for directing air currents outwardly between said gripping sections urging the articles into the overlying relation.

4. In a machine for removing film-like articles from a continuous, relatively high velocity source and stacking the articles in overlying relation on an outlet, the combination of: a plurality of U-shaped tubular arms, each of said arms having an article-gripping central section be-

tween spaced drive members, said gripping section including at least one outwardly directed inlet; a track having an arcuate section and a relatively straight section; means for engaging the drive members of each of said arms and driving said arms around said track with the article-gripping section projecting radially from the track and travelling along a path enclosing a zone, with the radius of the path of the article-gripping section many times that of the track in the arcuate section whereby the gripping section of an arm has a relatively high velocity when the arm is traversing the arcuate section of the track and a relatively low velocity when the arm is traversing the straight section, and with the gripping section of an arm passing through a first position adjacent the source at substantially the velocity of the source while 15 traversing said arcuate section and passing through a

10

5

second position adjacent the outlet at a greatly reduced velocity while traversing said straight section; control means for connecting a vacuum source to each arm while the arm is passing from said first position to said second position for gripping and transporting an article; and means positioned within said zone for directing an air stream outwardly between said gripping sections of said arms while said vacuum source is connected to the arms.
